ARC LAMP

Arthur J. Hatch, Toledo, Ohio, assignor to The Strong Electric Corporation, Toledo, Ohio, a corporation of Delaware

Application December 17, 1949, Serial No. 133,577

14 Claims. (Cl. 314—55)

1

My invention relates to arc lamps, and the principal object of my invention is to provide mechanism constructed and arranged to automatically maintain a substantially constant combined rate of feed of the lamp electrodes, thereby to automatically maintain the quality of the arc, and also to automatically maintain the arc substantially at a predetermined location.

In the drawings accompanying this specification and forming a part of this application I have shown for purposes of illustration what I now consider to be the best modes of carrying my invention into practice, and in these drawings:

Figure 1 is a partially diagrammatic view illustrating one such embodiment of my invention;

Figure 2 is a partially diagrammatic view illustrating a second such embodiment;

Figure 3 is a partially diagrammatic view illustrating a third such embodiment;

Figure 4 is a partially diagrammatic view illustrating a fourth such embodiment; and

Figure 5 is a partially diagrammatic view illustrating a fifth such embodiment.

As will be understood by those skilled in the art, my invention finds application particularly in respect of arc lamps of the types wherein the lamp comprises one or more reflectors or lenses or the like, constituting with the arc an optical system designed to produce a desired light formation, and wherein therefore it is necessary that the arc shall be maintained at a predetermined location, to properly coact with the remainder of the optical system.

However, commonly such lamps are designed for operation on direct current, and to produce a great preponderance of the light at a crater in the end of the positive electrode, and to utilize particularly the light emitted from this crater, and under these circumstances, maintaining the arc substantially at a predetermined location is essentially a matter of maintaining the tip or crater of the positive electrode substantially at a predetermined location.

Accordingly, although my invention is not limited thereto, I have illustrated it in respect of a lamp of the above described characteristics, and as functioning to automatically maintain the tip or crater of the positive electrode substantially at a predetermined location.

Therefore in each of the present embodiments I have indicated a positive electrode 11, a negative electrode 12, a reflector 13 positioned to receive the light from the crater 14 in the end of the positive electrode 11, and means 15 responsive to the position of the crater 14 to cause the crater 14 to automatically be maintained substantially at a predetermined location.

Further, although the control means 15 may be

2

any mechanism suitable for the purpose, in each of the present embodiments I have indicated it as comprising an electric switch 21 including a bi-metallic arm 22 and a cooperating stationary contact 23, a housing 24 enclosing the switch 21 and provided with an opening 25, and a lens 26 constructed and arranged, upon recession of the crater 14, to direct light from the crater 14 through the opening 25 onto the bi-metallic arm 22 and thereby cause the arm 22 to move into contact with the cooperating stationary contact 23 and close the switch 21.

Similarly, in each of the embodiments of Figures 1 through 4 I have shown the positive electrode 11 carried by a metal clamp 27 forming part of a positive electrode carrier 31, the negative electrode 12 carried by a metal clamp 28 forming part of a negative electrode carrier 32, and the positive and negative electrode carriers 31 and 32 supported and reciprocable by means of a pair of carrying and actuating shafts 33 and 34 each comprising a screw-threaded section 35 or 36 engaging respectively in a correspondingly screw-threaded opening 37 or 38 in one lateral portion of the positive or negative electrode carrier 31 or 32, and a smooth section 39 or 40 extending through a closely fitting opening 41 or 42 respectively in the other lateral portion of the negative electrode holder 32 and an integral boss 43, and in the other lateral portion of the positive electrode holder 31 and an integral boss 44.

Accordingly, rotation of the one shaft 33 will reciprocate the positive electrode holder 31 along the other shaft 34, thereby to advance or retract the positive electrode 11, and rotation of the other shaft 34 will reciprocate the negative electrode holder 32 along the one shaft 33, thereby to advance or retract the negative electrode 12, and the respective bosses 44 or 43 will operate to prevent cocking or binding of the electrode holder 31 or 32 and to insure direct reciprocation of the respective electrode 11 or 12.

With the foregoing, in the embodiment of Figure 1 the positive electrode 11 is connected by a main positive conductor 101 extending from the positive electrode clamp 27 to a positive connection terminal 102, the negative electrode 12 is connected by a main negative conductor 103 extending from the negative electrode clamp 28 to a negative connection terminal 104, and suitable rotation of the shafts 33 and 34, and thus suitable reciprocation of the positive and negative electrodes 11 and 12, are effected by means of a pair of shunt-connected direct-current motors 110 and 120.

As herein shown the motor 110 comprises a fixed frame 111, field coils 112 mounted on pole pieces 113 carried by the frame 111, an armature 114 and commutator 115 carried by a shaft 116 rotatable in bearings 117 supported by the frame

III, and brushes 118 and 119 mounted on the frame 111 and coacting with the commutator 115, and the motor 120 comprises a frame 121 carried by the shaft 116 of the motor 110, field coils 122 mounted on pole pieces 123 carried by the frame 121, an armature 124 and commutator 125 carried by a shaft 126 rotatable in bearings 127 supported by the frame 121, and brushes 128 and 129 mounted on the frame 121 and coacting with the commutator 125.

In the present embodiment the motor 120 is additionally supported by a fixed bracket 130 comprising an upstanding portion 131 carrying a bearing 132 receiving the outer end of the shaft 126 of the motor 120, and connection is made to the motor 120 by means of three slip rings mounted on the exterior of the motor frame 121 and engaged by contact brushes supported on the bracket 130, namely, a first ring 133 connected to one terminal of the field coils 122 and engaged by a first contact brush 134, a second ring 135 connected to the commutator brush 123 and engaged by a second contact brush 136, and a third ring 137 connected to the other terminal of the field coils 122 and the other commutator brush 129 and engaged by a third contact brush 138.

Further, in the present embodiment the shaft 116 of the motor 110 is connected to the negative electrode actuating shaft 34 by a suitable drive indicated by the reference numeral 140 and shown as including a suitable speed reducing mechanism 141, the shaft 126 of the motor 120 is connected to the positive electrode actuating shaft 33 by a suitable drive indicated by the reference numeral 142 and shown as including a suitable speed reducing mechanism 143, the armatures 114 and 124 of the motors 110 and 120 are connected directly to the main positive and negative conductors 101 and 103, the field coils 113 of the motor 110 are connected to the main positive and negative conductors 101 and 103 in series with an adjusting rheostat 144 and a control resistor 145, the field coils 123 of the motor 120 are connected to the main positive and negative conductors 101 and 103 in series with an adjusting rheostat 146, and the electric switch 21 of the control means 15 is connected in shunt across the control resistor 145.

As herein shown the above electrical connections are accomplished by a conductor 150 extending from the main positive conductor 101 to the commutator brush 119 of the motor 110, to one terminal of the field coils 113 of the motor 110, and to the contact brush 139 of the motor 120 and thereby to the brush 129 and one terminal of the field coils 123 of the motor 120, a conductor 151 extending from the main negative conductor 103 to the other commutator brush 118 of the motor 110, to one terminal of the adjusting rheostat 146 of the motor 120, and to the contact brush 136 of the motor 120 and thus to the commutator brush 123 of the motor 120, a conductor 152 extending from the other terminal of the adjusting rheostat 146 to the contact brush 134 of the motor 120 and thus to the other terminal of the field coils 123 of the motor 120, a conductor 153 extending from the other terminal of the field coils 113 of the motor 110 to one terminal of the adjusting rheostat 144 of the motor 110, a conductor 154 extending from the other terminal of the adjusting rheostat 144 to one terminal of the control resistance 145, a conductor 155 extending from the other terminal of the control resistance 145 to the main

negative conductor 103, a conductor 156 extending from the conductor 154 to the stationary contact 23 of the switch 21, and a conductor 157 extending from the bi-metallic arm 22 of the switch 21 to the main negative conductor 103.

With the described arrangement, the frame of the motor 110 being fixed, the shaft 116 of the motor 110 will rotate at the speed of the motor 110. However, the frame of the motor 120 being mounted on the shaft 116 of the motor 110, under the conditions that the motors 110 are connected to rotate in opposite directions and the speed of the motor 120 is always greater than the speed of the motor 110, the speed of the shaft 126 of the motor 120 will be numerically the speed of the motor 120 less the speed of the shaft 116 of the motor 110. On the other hand, the sum of the speeds of the shafts 116 and 126, being therefore the speed of the shaft 116 plus the speed of the motor 120 less the speed of the shaft 116, will always be numerically the speed of the motor 120.

Thus under the condition that the speed of the motor 120 is always greater than the speed of the motor 110, and inasmuch as the rates of feed of the positive and negative electrodes 11 and 12 are a fixed proportion respectively of the speed of the shaft 126 of the motor 120 and of the speed of the shaft 116 of the motor 110, therefore the sum of the rates of feed of the positive and negative electrodes 11 and 12 will always be numerically the fixed proportion of the speed of the motor 120, and on the other hand, the rate of feed of either electrodes will always be numerically the sum of the rates of feed of the two electrodes less the rate of feed of the other electrode.

Under these circumstances, with the described arrangement the adjusting rheostat 146 of the motor 120 is set to produce a speed of the motor 120 providing a combined rate of feed of the positive and negative electrodes 11 and 12 numerically equal to the sum of the burning rates of the two electrodes at the current at which the lamp is desired to be operated, and thus the two electrodes will automatically be fed at that rate, and therefore the quality of the arc will automatically be properly maintained.

However, to maintain the crater 14 of the positive electrode 11 at the proper location, the adjusting rheostat 144 of the motor 110 is set to produce a speed of the motor 110 and its shaft 116 such that the rate of feed of the negative electrode 12 is slightly greater than the actual burning rate, and therefore the rate of feed of the positive electrode 11 is slightly less than its actual burning rate.

Thus the crater 14 of the positive electrode 11 will begin to recede, but before it has proceeded sufficiently to depart from position to coact fully with the remainder of the optical system, light from the crater 14 will become directed by the lens 26 through the opening 25 in the switch housing 24, onto the bi-metallic arm 22 of the switch 21, and will cause the arm 22 to come into engagement with the cooperating stationary contact 23, thereby closing the switch 21 and shunting the control resistor 145, and consequently decreasing the speed of the motor 110, decreasing the rate of feed of the negative electrode 12, and increasing the rate of feed of the positive electrode 11.

The control resistance 145 being of suitable value, the altered rate of feed of the positive electrode 11 will be slightly greater than its actual

rate of burning, and thus the crater 14 will become restored to its previous position, whereupon the lens 26 will no longer direct light from the crater 14 through the opening 24, the arm 22 will withdraw from the cooperating stationary contact 23 and convert the switch 21 to open condition, and thus the shunt will be removed from the control resistor 213, and the mechanism will be restored to its previous condition.

Thus the described embodiment functions automatically both to maintain proper total feed of the electrodes and also to maintain the arc at the proper location, and thus to automatically maintain both proper quality of the arc and optical relation.

In the embodiment of Figure 2 the positive electrode 11 is connected by a main positive conductor 201 extending from the positive electrode clamp 27 to a positive connection terminal 202, and the negative electrode 12 is connected by a main negative conductor 203 extending from the negative electrode clamp 28 to a negative connection terminal 204, and suitable rotation of the shafts 33 and 34, and thus suitable reciprocation of the positive and negative electrodes 11 and 12, are effected by main and auxiliary shunt-connected direct-current motors 205 and 206 having their armatures 207 and 208 connected directly across the main positive and negative conductors 201 and 203 and their fields 209 and 210 connected across the conductors 201 and 203 in series respectively with a main motor adjusting rheostat 211 and with an auxiliary motor adjusting rheostat 212 and a control resistance 213 arranged to be shunted by the switch 21.

As herein shown the above electrical connections are accomplished by a conductor 220 extending from the main positive conductor 201 to one terminal of the control resistance 213, one terminal of the auxiliary motor armature 208, one terminal of the main motor adjusting rheostat 211, and one terminal of the main motor armature 207, a conductor 221 extending from the other terminal of the main motor adjusting rheostat 211 to one terminal of the main motor field 209, a conductor 222 extending from the other terminal of the main motor armature 207 and the other terminal of the main motor field 209, to the main negative conductor 203, a conductor 223 extending from the other terminal of the control resistance 213 to one terminal of the auxiliary motor adjusting rheostat 212, a conductor 224 extending from the other terminal of the auxiliary motor control rheostat 212 to one terminal of the auxiliary motor field 210, a conductor 225 extending from the other terminal of the auxiliary motor armature 208 and the other terminal of the auxiliary motor field 210, to the main negative conductor 203, a conductor 226 extending from one terminal of the control resistance 213 to the bi-metallic arm 22 of the switch 21, and a conductor 227 extending from the other terminal of the control resistance 213 to the cooperating stationary contact 23 of the switch 21.

For the purpose of operating the shafts 33 and 34 the present embodiment comprises a pair of discs 230 and 240 each provided on one face with an integral hub 231 or 241 receiving the adjacent end of the respective shaft 33 or 34, each secured to the respective shaft 33 or 34 by a pin 232 or 242 traversing the hub 231 or 241 and the shaft 33 or 34, each provided in its other face with a central bearing recess 233 or 243 rotatably supporting one end of a relevant drive shaft 234

or 244, and each carrying a pair of studs 235 or 245 rotatably mounting pinions 236 or 246 engaging a cooperating sun gear 237 or 247 fixed to the respective drive shaft 234 or 244, and further a pair of arms 238 and 248 each freely rotatable on the respective drive shaft 234 or 244 and each carrying a double ring gear 239 or 249 engaging interiorly with the respective pinions 236 or 246 and exteriorly with a common interconnecting gear 260.

For the same purpose the present embodiment comprises further a shaft 261 operated by the main motor 205 and provided with a pair of worms 262 and 263 coacting respectively with worm gears 264 and 265 carried by the drive shafts 234 and 244, a shaft 266 driven by the auxiliary motor 206 and provided with a worm 267 cooperatively engaging a worm gear 268 fixed to a jack shaft 269, and a worm 270 carried by the jack shaft 269 and cooperatively engaging a worm wheel 271 fixed to a shaft 272 on which is mounted the interconnecting gear 260 engaged by the external teeth of the ring gears 239 and 249.

With the above arrangement, the pitch and direction of the worms and threads, and the number of teeth in the gears and pinions, are selected so that upon operation of the main motor 205 at a proper speed and in the proper direction, regardless of the auxiliary motor 206, the electrodes 11 and 12 will be fed at a combined rate numerically equal to the combined rate at which they are consumed at the current at which the lamp is desired to operate, and on the other hand, that upon operation of the auxiliary motor 206 with the main motor 205 stationary, the positive electrode 11 would be retracted, and the negative electrode 12 would be advanced, and both at the same rate, thus effecting no change in the spacing of the electrodes, but resulting in shifting the location of the arc.

Accordingly, in the present embodiment, each of the motors 205 and 206 being connected to rotate in the proper direction, first the main motor adjusting rheostat 211 is set to effect operation of the main motor 205 at the speed to feed the electrodes 11 and 12 at the combined rate numerically equal to the combined rate at which they are consumed at the current at which the lamp is desired to operate, and then the auxiliary motor adjusting rheostat 212 is set to effect operation of the auxiliary motor 206 at a speed slightly greater than the speed at which the ratio of the rate of feed of the positive electrode 11 to the rate of feed of the negative electrode 12 would be exactly equal to the ratio at which the respective electrodes are consumed.

Thus the crater 14 of the positive electrode 11 will begin to recede, but before it has proceeded materially, light from the crater 14 will become directed by the lens 26 through the opening 25 in the switch housing 24, onto the bi-metallic arm 22 of the switch 21, and will cause the arm 22 to come into engagement with the cooperating stationary contact 23, thereby closing the switch 21 and shunting the control resistor 213, resulting in decreasing the speed of the auxiliary motor 206, thus increasing the rate of feed of the positive electrode 11 and equally decreasing the rate of feed of the negative electrode 12.

The control resistance 213 being of proper value, thereupon the rate of feed of the positive electrode 11 will be slightly greater, and the rate of feed of the negative electrode 12 equally less, than the rates at which the respective elec-

trodes are being consumed, and thus the crater 14 will become restored to its previous position, whereupon the lens 26 will no longer direct light from the crater 14 through the opening 24, the arm 22 will withdraw from the cooperating stationary contact 23, the shunt will be removed from the control resistor 213, and the mechanism will be restored to its previous condition.

Accordingly the embodiment of Figure 2 also operates automatically both to maintain proper total feed of the electrodes and to maintain the arc at the proper location, and thus to automatically maintain both proper quality of the arc and proper optical relation.

In the embodiment of Figure 3 the positive electrode 11 is connected by a main positive conductor 301 extending from the positive electrode clamp 27 to a positive connection terminal 302, the negative electrode 12 is connected by a main negative conductor 303 extending from the negative electrode clamp 28 to a negative connection terminal 304, and suitable rotation of the shafts 33 and 34, and thus suitable reciprocation of the positive and negative electrodes 11 and 12, are effected by first and second shunt-connected direct-current motors 305 and 306 having their armatures 307 and 308 connected directly across the main positive and negative conductors 301 and 303 and their fields 309 and 310 connected across the main conductors 301 and 303 in series respectively with a first motor adjusting rheostat 311 and a control resistance 313 arranged to be shunted by the switch 21, and with a second motor adjusting rheostat 312.

As herein shown the above electrical connections are accomplished by a conductor 320 extending from the main positive conductor 301 to one terminal of the first motor armature 307 and one terminal of the control resistance 313, a conductor 321 extending from the other terminal of the control resistance 313 to one terminal of the first motor adjusting rheostat 311, a conductor 322 extending from the other terminal of the first motor adjusting rheostat 311 to one terminal of the first motor field 309, a conductor 323 extending from the other terminal of the first motor armature 307 and the other terminal of the first motor field 309, to the main negative conductor 303, a conductor 324 extending from the main positive conductor 301 to one terminal of the second motor armature 308 and one terminal of the second motor adjusting rheostat 312, a conductor 325 extending from the other terminal of the second motor adjusting rheostat 312 to one terminal of the second motor field 310, a conductor 326 extending from the other terminal of the second motor armature 308 and the other terminal of the second motor field 310, to the main negative conductor 303, a conductor 327 extending from the conductor 320 to the cooperating stationary contact 23 of the switch 21, and a conductor 328 extending from the bi-metallic arm 22 of the switch 21 to the conductor 321.

For the purpose of operating the negative electrode shaft 34 the present embodiment comprises a shaft 330 operated by the first motor 305 and provided with a worm 331 engaged with a worm wheel 332 carried by a jack shaft 333, and a worm 334 carried by the jack shaft 333 and engaged with a worm wheel 335 carried by a sleeve 336 secured to the shaft 34 in any suitable manner, as by a pin 337 traversing the sleeve 336 and the shaft 34.

For the purpose of conjointly operating the positive electrode shaft 33 the present embodiment comprises a shaft 340 operated by the second motor 306 and provided with a worm 341 engaged with a worm wheel 342 carried by a jack shaft 343, a worm 344 carried by the jack shaft 343 and engaged with a worm wheel 345 carried by a sleeve 346 journaled on the shaft 33 and provided with a sun gear 347, an arm 348 fixed to the shaft 33 by means of a traversing pin 349 and carrying pinions 350 meshing with the sun gear 347 and with the internal teeth of a duplex ring gear 351 carried by a disc 352 journaled on the sleeve 346, and a gear 353 meshing with the external teeth of the ring gear 351, provided with a hub 354, and secured to the shaft 34 by means of a pin 355 traversing the hub 354 and the shaft 34.

With the above arrangement the number of teeth in the various gears and pinions interconnecting the sleeves 336 and 346, is selected so that upon rotation of the sleeve 336 in the direction to advance the negative electrode 12, but with the sleeve 346 stationary, the positive electrode 11 would be retracted at the same rate at which the negative electrode 12 is advanced.

Accordingly, in the present embodiment, each of the motors 305 and 306 being connected to rotate in the proper direction, first the first motor 305 adjusting rheostat 311 is set to effect operation of the first motor 305 at a speed slightly greater than the speed necessary to feed the negative electrode 12 at the rate at which it will be consumed at the current at which the lamp is desired to operate, and then the second motor 306 adjusting rheostat 312 is set to effect operation of the second motor 306 at the speed proper to feed the positive electrode 11 at such rate that the combined rates of feed of the two electrodes 11 and 12 will be numerically equal to the combined rates at which the electrodes 11 and 12 will be consumed at the designated current.

Thus the two electrodes will automatically be maintained at the predetermined spacing, and the quality of the arc will be maintained, but the arc will begin to shift in the direction of advance of the negative electrode, and the crater 14 will begin to recede from the proper position to coincide fully with the remainder of the optical system.

However, before this has proceeded to any material extent, light from the crater 14 will become directed by the lens 26 through the opening 24 in the switch housing 21, onto the bi-metallic arm 22 of the switch 21, and will cause the arm 22 to come into engagement with the cooperating stationary contact 23, thereby closing the switch 21 and shunting the control resistor 313, resulting in decreasing the speed of the first motor 305 and thereby decreasing the rate of feed of the negative electrode 12 and correspondingly increasing the rate of feed of the positive electrode 11.

The control resistance 313 being of proper value, thereupon the rate of feed of the positive electrode 11 will be slightly greater, and the rate of feed of the negative electrode 12 equally less, than the respective rates at which they are to be consumed, and thus the crater 14 will become restored to its previous position, whereupon the lens 26 will no longer direct light from the crater 14 through the opening 24, the arm 22 will withdraw from the stationary contact 23, the shunt will be removed from the control resistor 313, and the mechanism will be restored to its previous condition.

Accordingly the embodiment of Figure 3 also operates automatically to maintain both proper total feed of the electrodes and proper location of the arc, and therefore to automatically maintain both proper quality of the arc and proper optical relation.

In the embodiment of Figure 4 the positive electrode 11 is connected by a main positive conductor 401 extending from the positive electrode clamp 27 to a positive connection terminal 402, the negative electrode 12 is connected by a main negative conductor 403 extending from the negative electrode clamp 28 to a negative connection terminal 404, rotation of the shaft 33, and thus reciprocation of the positive electrode 11, are effected by a shunt-connected direct-current motor 410 comprising a rotary armature 411 and a stationary field 412 and having its armature 411 connected to the shaft 33 by a transmission indicated at 413 and shown as including a suitable speed reduction mechanism 414, and rotation of the shaft 34, and thus reciprocation of the negative electrode 12, are effected by a shunt-connected direct-current motor 420 comprising a rotary armature 421 and a stationary field 422 and having its armature 421 connected to the shaft 34 by a transmission indicated at 423 and shown as including a suitable speed reduction mechanism 424.

In this embodiment each of the motor armatures 411 and 421 is connected directly between the main positive and negative conductors 401 and 403, each of the motor fields 412 and 422 is connected between the main conductors 401 and 403 in series with a suitable fixed resistor 415 or 425 and a control rheostat 416 or 426, and each of the rheostats 416 or 426 comprises a main winding 417 or 427, a compensating winding 418 or 428 connected to the circuit at the same end at which the respective main winding 417 or 427 is connected, and a bridge 419 or 429 effecting electrical connection between the two windings of the respective rheostat 416 or 426 and adjustable longitudinally of the windings thus to adjust the portions of the windings included in circuit.

As herein shown the above electrical connections are accomplished by a conductor 430 extending from the main positive conductor 401 to one terminal of the first motor armature 411, one terminal of the first motor field 412, one terminal of the second motor armature 421, and one terminal of the second motor field 422, a conductor 431 extending from the other terminal of the first motor field 412 to the one end of the first rheostat main winding 417, a conductor 432 extending from the corresponding end of the first rheostat compensating winding 418 to one terminal of the first fixed resistor 415, a conductor 433 extending from the other terminal of the second motor field 422 to the one end of the second rheostat main winding 427, a conductor 434 extending from the corresponding end of the second rheostat compensating winding 428 to one terminal of the second fixed resistor 425, and a conductor 435 extending from the other terminal of the first motor armature 411, the other terminal of the first fixed resistor 415, the other terminal of the second motor armature 421, and the other terminal of the second fixed resistor 425, to the main negative conductor 403.

However, the present embodiment comprises also an electromagnetic switch 440 including an actuating coil 441 responsive to the condition of the control switch 21 and to that purpose con-

nected between the main positive and negative conductors 401 and 403 in series with the switch 21, and a switch arm 442 responsive to the condition of the coil 441, arranged to be in engagement with a normal contact 443 when the coil 441 is not energized and to be brought into engagement with an alternate contact 444 when the coil 441 is energized, and connected in the one position to shunt the first fixed resistor 415 and the in-circuit portion of the first rheostat compensating winding 418, and in the other position to shunt the second fixed resistor 425 and the in-circuit portion of the second rheostat compensating winding 428.

As herein shown the foregoing connections are accomplished by a conductor 450 extending from the branch positive conductor 430 to one terminal of the coil 441, a conductor 451 extending from the other terminal of the coil 441 to the stationary contact 23 of the control switch 21, a conductor 452 extending from the bi-metallic arm 22 of the switch 21 to the main negative conductor 403, a conductor 453 extending from the first rheostat bridge 419 to the normal contact 443, a conductor 454 extending from the second rheostat bridge 429 to the alternate contact 444, and a conductor 455 extending from the switch arm 442 to the branch negative conductor 435.

With the described arrangement the first rheostat 416 is set so that with the switch 442 in the position shown, the first motor 410 will operate at a speed which taken in conjunction with the ratio of the first speed reducing mechanism 414, will feed the positive electrode 11 at a rate slightly less than the rate at which that electrode will be consumed at the current at which the lamp is desired to operate, and then the second rheostat 426 is set so that with the switch 442 in the position shown, the second motor 420 will operate at that speed which taken in conjunction with the ratio of the second speed reducing mechanism 424, will feed the negative electrode 12 at a rate such that the combined rates of feed of the two electrodes 11 and 12 will be numerically equal to the combined rates at which the two electrodes 11 and 12 will be consumed at the indicated current.

Thus the two electrodes will automatically be maintained at the correct spacing, and the quality of the arc will be maintained, but the arc will begin to shift in the direction of advance of the negative electrode, and the crater 14 will begin to recede from the proper position relative to the remainder of the optical system.

However, before this has proceeded to any material extent, the light from the crater 14 will become directed by the lens 26 through the opening 25 in the switch housing 24, onto the bi-metallic arm 22 of the switch 21, and will cause the arm 22 to come into engagement with the cooperating contact 23, thereby closing the switch 21 and completing the circuit through the coil 441 of the electro-magnetic switch 440, thus shifting the switch arm 442 from its position in engagement with the normal contact 443 to the position in engagement with the alternate contact 444, removing the shunt from the first fixed resistor 415 and the in-circuit portion of the first rheostat compensating winding 418 and imposing a shunt on the second fixed resistor 425 and the in-circuit portion of the second rheostat compensating winding 428.

As will be understood, this will result in decreasing the current in the field 412 of the first motor 410 and increasing the current in the field

422 of the second motor 420, thus increasing the speed of the first motor 410 and consequently the rate of feed of the positive electrode 11, and decreasing the speed of the second motor 420 and consequently the rate of feed of the negative electrode 12.

Under these circumstances, the fixed resistances 415 and 425 and compensating resistances 418 and 428 are selected so that in any position of the resistor bridges 419 and 429, the change in speed of the first motor 410 will be sufficient to cause the positive electrode 11 to be fed at a rate greater than the rate at which it is being consumed, thus gradually to restore it to its desired position, and also that the concurrent reduction in the rate of feed of the negative electrode 12 will be numerically equal to the increase in the rate of feed of the positive electrode 11, thereby to continue to maintain the proper gap between the electrodes 11 and 12 and thus the proper quality of the arc.

As will also be understood, when the crater 14 has become restored to its desired position, the lens 26 will no longer direct light from the crater 14 through the opening 24, the arm 22 will withdraw from the stationary contact 23, the coil 441 of the electro-magnetic switch 440 will no longer be energized, and the mechanism will be restored to its previous condition.

Accordingly the embodiment of Figure 4 also operates to automatically maintain both proper quality of the arc and proper position of the crater 14 of the positive electrode 11, and thus to automatically maintain both proper quality of the arc and proper position.

In the embodiment of Figure 5 the positive and negative electrodes 11 and 12 are carried by metal clamps 501 and 502 forming parts of positive and negative electrode carriers 503 and 504 reciprocably mounted on a pair of supporting rods 505 extending through openings 506 in the carriers 503 and 504, are connected by main positive and negative conductors 507 and 508 extending from the respective clamps 501 and 502 to a positive connection terminal 509 and a negative connection terminal 510, and are fed by mechanism comprising a shaft 511 rotatably mounted on the positive electrode carrier 503, a shaft 512 rotatably mounted on the negative electrode carrier 504, large worm gears 513 and 514 fixed to the shafts 511 and 512, a duplicate small worm gears 515 and 516 connected to the shafts 511 and 512 through suitable friction clutches not shown, a main shaft 520 comprising a screw-threaded section 521 cooperatively engaging the positive carrier gear 513 and a reversely screw-threaded section 522 cooperatively engaging the negative carrier gear 514, and an auxiliary shaft 530 comprising duplicate screw-threaded sections 531 and 532 cooperatively engaging the duplicate gears 515 and 516.

Under these circumstances the shafts 520 and 530 are intended to rotate in the directions indicated by the arrows appearing on the respective shafts, and rotation of the shaft 520 in the indicated direction will rotate the gears 513 and 514 in the directions indicated by the arrows appearing on the respective gears, and in the present embodiment such rotation of the shaft 520 is accomplished by a worm gear 523 carried by the shaft 520 and operated by a coacting worm 524 fixed to a jack shaft 525, and a worm gear 526 carried by the jack shaft 525 and operated by a coacting worm 527 provided on the shaft 528 of the armature 541 of a main

shunt-connected direct-current motor 540, and similarly rotation of the auxiliary shaft 530 is accomplished by a worm gear 533 carried by the shaft 530 and operated by a coacting worm 534 fixed to a jack shaft 535, and a worm gear 536 carried by the jack shaft 535 and operated by a coacting worm 537 provided on the shaft 530 of the armature 551 of an auxiliary shunt-connected direct-current motor 550.

According to the present embodiment the main motor 540 has its armature 541 connected across the main positive and negative conductors 507 and 508 and its field 542 connected across these conductors 507 and 508 in series with a main motor adjusting rheostat 543, the auxiliary motor 550 has its armature 551 connected across the main conductors 507 and 508 and its field 552 connected across these conductors 507 and 508 in series with an auxiliary motor adjusting rheostat 553 and a control resistor 554, and the switch 21 is connected to shunt the control resistor 554.

As herein shown the above connections are accomplished by a conductor 545 extending from the main positive conductor 507 to one terminal of the main motor armature 541 and one terminal of the main motor field 542, a conductor 546 extending from the other terminal of the main motor field 542 to one terminal of the main motor adjusting rheostat 543, a conductor 547 extending from the other terminal of the main motor armature 541 and the other terminal of the main motor adjusting rheostat 543, to the main negative conductor 508, a conductor 555 extending from the main positive conductor 507 to one terminal of the auxiliary motor armature 551 and one terminal of the control resistor 554, a conductor 556 extending from the other terminal of the auxiliary motor armature 551 to the main negative conductor 508, a conductor 557 extending from the other terminal of the control resistor 554 to one terminal of the auxiliary motor adjusting rheostat 553, a conductor 558 extending from the other terminal of the auxiliary motor adjusting rheostat 553 to one terminal of the auxiliary motor field 552, a conductor 559 extending from the other terminal of the auxiliary motor field 552 to the main negative conductor 508, and conductors 560 and 561 extending from the terminals of the control resistor 554 to the bi-metallic arm 22 and stationary contact 23 of the switch 21.

With the foregoing the pitch of the positive carrier thread 521 and the pitch of the negative carrier thread 522 are such that the ratio to the pitch of the negative carrier thread 522 is somewhat greater than the highest ratio of the rates at which the respective electrodes 11 and 12 will be consumed at any current at which the lamp is constructed to be operated.

Under this condition, if the shafts 520 and 530 are rotated in the indicated directions and at exactly the speeds proportional to the respective gears 521-513 and 531-515, obviously each of the shafts 520 and 530 would operate to rotate the positive carrier shaft 511 at the same speed and in the same direction, and merely the positive carrier shaft 511 would rotate, and the positive carrier 503 would remain stationary. However, in such event the negative carrier 504 would be very rapidly advanced.

On the other hand, if the shaft 530 is rotated at a lesser speed than the above proportionate speed, the positive carrier 503 will be correspondingly advanced, and the rate of advance of the

negative carrier 504 will be equally decreased, and thus the speed of rotation of the auxiliary shaft 530 determines the distribution between the electrodes 11 and 12 of the total feed determined by the speed of rotation of the main shaft 520.

Accordingly, the main motor adjusting rheostat 543 is set to effect rotation of the main motor 540 at that speed at which the combined rates of feed of the positive and negative electrodes 11 and 12 are numerically equal to the combined rates at which the electrodes 11 and 12 will be consumed at the current at which the lamp is desired to operate, and then the auxiliary motor rheostat 553 is set to effect rotation of the auxiliary motor 550 at a speed at which the rate of feed of the positive electrode 11 is slightly less, and the rate of feed of the negative electrode 12 is slightly greater, than the rates at which the respective electrodes 11 and 12 will be consumed at the indicated current.

Thus the two electrodes 11 and 12 will automatically be maintained at the predetermined spacing, and the quality of the arc will be maintained, but the arc will begin to shift in the direction of advance of the negative electrode, and the crater 14 will begin to recede from the proper position to coact fully with the remainder of the optical system.

However, before this has proceeded to any material extent, light from the crater 14 will become directed by the lens 26 through the opening 25 in the switch housing 24, onto the bi-metallic arm 22 of the switch 21, and will cause the arm 22 to come into engagement with the cooperating stationary contact 23, thereby closing the switch 21 and shunting the control resistor 554, resulting in decreasing the speed of the auxiliary motor 550 and thereby decreasing the rate of feed of the negative electrode 12 and correspondingly increasing the rate of feed of the positive electrode 11.

The control resistance 554 being of proper value, thereupon the rate of feed of the positive electrode 11 will be slightly greater, and the rate of feed of the negative electrode 12 equally less, than the respective rates at which they are being consumed, and thus the crater 14 will become restored to position, whereupon the lens 26 will no longer direct light from the crater 14 through the opening 24, the arm 22 will withdraw from the stationary contact 23, the shunt will be removed from the control resistance 554, and the mechanism will be restored to its previous condition.

Accordingly the embodiment of Figure 5 also operates automatically to maintain both proper total feed of the electrodes and proper location of the arc, and therefore to automatically maintain both proper quality of the arc and proper optical relation.

Therefore each of the described embodiments accomplishes at least the principal object of my invention. On the other hand, each of the described embodiments can be variously changed and modified, also other embodiments may be substituted, all without departing from the purpose and scope of my invention, and thus my invention is not to be regarded as limited to the present disclosure, but the present disclosure is illustrative only, and I claim as my invention:

1. An arc lamp comprising two electrodes constructed and arranged to function as terminals of an arc, electrically energizable means constructed and arranged to automatically and continuously feed said electrodes at a substantially

constant combined rate, and capable of change of the ratio between the respective rates of feed while maintaining the combined rate substantially constant, and means constructed and arranged to control the electrically energizable electrode feeding means to automatically change said electrode feed rate ratio in response to change in position of the arc.

2. An arc lamp comprising two electrodes constructed and arranged to function as terminals of an arc, electrically energized means constructed and arranged to continuously and automatically feed said electrodes at a substantially constant combined rate, adjustable to change said rate, and capable of change of the ratio between the respective rates of feed of said electrodes while maintaining the combined rate substantially constant, and thermo-responsive means constructed and arranged to control the electrically energized means to automatically change said electrode feed ratio in response to change in position of the arc.

3. An arc lamp comprising two electrodes constructed and arranged to function as terminals of an arc, means constructed and arranged to continuously and automatically feed said electrodes at a substantially constant combined rate substantially equal to the rate at which said electrodes will be consumed at the current at which the lamp is desired to be operated, thereby to automatically maintain the quality of the arc, and capable of change of the ratio between the respective rate of feed while maintaining the combined rate substantially constant, and thermo-responsive means constructed and arranged to control the electrode feeding means to automatically change said ratio in response to change in position of the arc.

4. An arc lamp comprising two electrodes constructed and arranged to function as terminals of an arc, electrically energized means constructed and arranged to continuously and automatically feed said electrodes at a substantially constant combined rate substantially equal to the rate at which said electrodes will be consumed at the current at which the lamp is desired to be operated, thereby to automatically maintain the quality of the arc, and to normally feed said electrodes at differential rates of a rate ratio different from the rate ratio at which said electrodes will be consumed at such current, and capable of change of said ratio while maintaining the combined rate substantially constant, and thermo-responsive means constructed and arranged to control the electrically energized means to automatically change said electrode feed ratio in response to a relative change in position of the arc and to a ratio different from the ratio at which said electrodes will be consumed at such current but departing in the inverse direction.

5. An arc lamp comprising two electrodes constructed and arranged to function as terminals of an arc, electrically energized means constructed and arranged to continuously and automatically feed said electrodes at a substantially constant combined rate, adjustable to set said rate to be substantially equal to the rate at which said electrodes will be consumed at the current at which the lamp is desired to be operated, thereby to automatically maintain the quality of the arc, means for changing the ratio between the respective rates of feed of the individual electrodes while maintaining the combined rate substantially constant, and means constructed and arranged to control the electrically energized means to

automatically change said electrode feed ratio in response to change in position of the arc.

6. An arc lamp comprising two electrodes constructed and arranged to function as terminals of an arc, means including a pair of electrically energized motors constructed and arranged to continuously and automatically feed said electrodes at a substantially constant combined rate, adjustable to change said rate, and capable of change of the ratio between the respective rates of feed while maintaining the combined rate substantially constant, and circuit controlling means for said motors constructed and arranged to automatically change said electrode feed ratio in response to change in position of the arc and thereby to automatically maintain the arc substantially at a given position. 15

7. An arc lamp comprising two electrodes constructed and arranged to function as terminals of an arc, means constructed and arranged to continuously and automatically feed said electrodes at a substantially constant combined rate substantially equal to the rate at which said electrodes will be consumed at the current at which the lamp is desired to be operated, thereby to automatically maintain the quality of the arc, and capable of change of the ratio between the respective rates of feed while maintaining the combined rate substantially constant, and means constructed and arranged to control said electrode feeding means to automatically change said electrode feed rate ratio in response to change in position of the arc and thereby to automatically maintain the arc substantially at a given position. 25

8. An arc lamp comprising two electrodes constructed and arranged to function as terminals of an arc, means constructed and arranged to continuously and automatically feed said electrodes at a substantially constant combined rate, and thermo-responsive means constructed and arranged to control said electrode feeding means to automatically maintain the arc substantially at a given position. 30

9. An arc lamp comprising two electrodes constructed and arranged to function as terminals of an arc, means including a pair of electrically energized motors constructed and arranged to continuously and automatically feed said electrodes at a substantially constant combined rate substantially equal to the combined rate at which said electrodes will be consumed at the current at which said lamp is desired to be operated, thereby to automatically maintain the quality of the arc, and means intercalated in a circuit of one of said motors constructed and arranged to automatically maintain the arc substantially at a given relative position. 35

10. An arc lamp comprising two electrodes constructed and arranged to function as terminals of an arc, means constructed and arranged to continuously and automatically feed said electrodes at a substantially constant combined rate, and adjustable to set said rate to be substantially equal to the combined rate at which said electrodes will be consumed at the current at which said lamp is desired to be operated, thereby to automatically maintain the quality of the arc, and means responsive to a change in relative position of the arc constructed and arranged to control said electrode feeding means to auto- 40

matically return the arc to its normal position.

11. An arc lamp to operate on direct current, comprising a positive electrode and a negative electrode constructed and arranged to form the terminals of an arc, means constructed and arranged to continuously and automatically feed said electrodes at a substantially constant combined rate, and capable of change of the ratio between the respective rates of feed while maintaining the combined rate substantially constant, and thermo-responsive means constructed and arranged to automatically change said electrode feed rate ratio in response to change in position of the tip of said positive electrode. 10

12. An arc lamp to operate on direct current, comprising a positive electrode and a negative electrode constructed and arranged to form the terminals of an arc, electrically energized means constructed and arranged to continuously and automatically feed said electrodes at a substantially constant combined rate, and capable of change of the ratio between the respective rates of feed while maintaining the combined rate substantially constant, and means associated with said electrically energized means constructed and arranged to automatically change said ratio responsive to change in the relative position of the tip of said positive electrode and thereby to automatically maintain the tip of said positive electrode substantially at a given location. 20

13. An arc lamp comprising a positive electrode and a negative electrode constructed and arranged to form the terminals of an arc; means individual to each electrode for continuously feeding said electrodes at a substantially constant combined rate; means for varying the feed rate of the individual electrode feeding means without affecting the combined rate of feed of the electrodes, and thermo-responsive means dependent for operation upon the relative position of the arc for controlling the feed rate of the individual electrode feeding means. 30

14. An arc lamp including two electrodes constructed and arranged to function as terminals of an arc; means individual to each electrode for continuously feeding the electrodes to arc forming position; said feeding means coacting to feed said electrodes at a substantially constant combined rate; means for automatically changing the feed rate ratio of said individual electrode feeding means without affecting the constant combined rate, and thermo-responsive means controlled by the relative position of the arc for changing the feed rate ratio of the electrode feeding means. 40
